By B. Linger, Atty.

UNITED STATES PATENT OFFICE.

PAUL NATTKÄMPFER, OF PILLKALLEN, GERMANY.

PAVING TILE.

Application filed June 19, 1926, Serial No. 117,101, and in Germany June 29, 1925.

The present invention relates to a pavement, paving stone or plate for forming the surface of streets, water courses, gullies and the like. It is particularly suitable for forming cylindrically curved surfaces, such as those of streets or footpaths at the part where they curve upwards or those of water courses where they curve downwards to form an open channel.

10 The object of the invention is to provide a joint between adjacent plates that can be kept closed. To achieve this, the plates are given such a shape that in plan view they appear to have a trapezoidal outline. This enables joints between adjacent plates to be tightened by pushing the plates from opposite sides of the pavement until a tight joint is obtained. Flat trapezoidal plates for lateral displacement are known, but the known arrangement does not suffice for cylindrically shaped plates, because the concentrical position of the plates has to be retained when the plates are subsequently moved laterally, otherwise the curved surfaces of the pavement will not remain continuous. To achieve this, the converging sides of the plates are provided with guiding means, which enable the plates to retain their concentric position when transversely displaced.

20 Furthermore the novel pavement or covering enables its direction to be changed as desired without having to use plates of special shape for that purpose. To effect this, the trapezoidal plates are alternately displaced by 180° in their plane along a straight pavement, so that, of the two parallel sides of the plates, the short side of one plate is contiguous to a long side of the next plate. To form a curve or bend in the longitudinal direction of the pavement or covering, two or more plates are so placed in juxtaposition without the said relative displacement of 180° that their longer parallel sides lie along the outer edge of the bend or curve. In order to give the latter the desired radius, narrow plates can be used, for example their parallel sides can be a quarter, half or three quarters as long as in a standard plate.

30 The means used for interconnecting adjacent plates must be so devised that the plates can be rotated 180° in the plane of

the pavement. Although such means are specially suitable for curved plates, they are of course also applicable to flat plates. 55

In the figures of the annexed drawings several embodiments and details of the invention are shown.

Figure 1 is a plan view of a paving tile or plate of normal size and cylindrical shape. 60

Figures 2 and 3 are side views of this plate.

Figure 4 shows a plate adapted to join two rows of pavement of different sizes.

Figures 5 and 6 are a plan and a side 65 view of a drain for waste-waters.

Figures 7 and 8 show in a smaller scale a plan and a side view of a simple completely flat plate.

Figure 9 shows an example of the pavement of a street in a still smaller scale. 70

Figure 10 is in the same scale an example of the lining of the bottom of a small water course.

Figure 11 shows on an enlarged scale an 75 embodiment of a junction of two plates.

Fig. 12 is a section following the line I—I in Fig. 11.

Fig. 13 is a front view of another junction; 80

Fig. 14 the same view of a somewhat modified form.

Figure 15 shows a detail.

In the Figures 1 and 7 plates of normal size and form are shown. They are trapezoidal shaped in the plan view and are bordered by two parallel sides *a*, *b* and two converging sides *c*, *d* which involve the wedge effect of the plate. 85

The arrows in the Figures 1, 4, 5, 9 and 90 10-14 serve to indicate the longitudinal direction of the water course, the street or drain and so on and at the same time the longitudinal direction of a single paving tile corresponding to the sides *a* and *b*.

As shown in Figures 9 and 10 the longitudinal edges *a*, *b* of two following tiles 1, 2 are running in a straight line in case, where the longer edge *b* of the first tile 1 is in juxtaposition with the shorter edge *a* of the other tile 2. In this case one of the two plates lying side by side is turned by an angle of 180°. The longitudinal edges of two neighboring tiles 1 and 2 will follow 95 100

a circle or a curve, in the case where the longer edge b is laid in line with the longer edge b of the other tile, the curve may be directed in such case either in the one or in the other direction.

The arch-wise composition of tiles or plates 1 and 2 of full sizes in combination with plates 3 of $\frac{3}{4}$ size, plates 4 of $\frac{1}{2}$ size and plates 5 of $\frac{1}{4}$ size (see Fig. 10) results in arcs of different radius, which can easily be chosen in accordance with the courses of sheets, ditches or the like. In curves of higher degrees combinations of several subdivisions of the whole length are employed, the outline of flat curves is obtained by combining three tiles in a straight line or by five tiles in the same manner and by connecting together single and multiple lengths arcwise.

Figure 4 shows an intermediate plate used if a water course is to be rendered broader or narrower for example before or behind bridges. In stones or piles of this kind the sides a' , b' lying in the longitudinal direction are inclined against each other. The other sides c , d are of the same inclination as in other plates.

The enlargement of the joints after the construction of the pavement is due to the solidifying of the concrete and to the heating by the rays of the sun or by movements of the ground. When the usual square tiles or polygonal tiles are employed the latter enlargements of the joints cannot be mended or compensated because such compensation would necessitate a considerable displacement of a great number of tiles even at very short distances.

The joints generated in constructing a pavement by means of the present trapezoidal tiles are subjected to a wedge-like action and may therefore easily be tightened by afterwards moving the plates in transverse direction and so driving together the wedge shaped edges, for this purpose only a slight displacement of each tile being necessary.

As shown in Figures 2, 3 and 10 the tiles or plates for water courses or drains are cylindrically shaped. Thus a channel or gully may be formed with them. These plates are in the first line for ditches of little inclination used for the purpose of draining fields and meadows.

The angular shape of the plate shown in Figures 5 and 6 will be used preferably for leading off waste waters in towns.

The flat plates corresponding to Figures 7 and 8 are laid in streets or in water courses with a broader even bottom.

The plates can be composed of two parts 6 and 7 as shown in Figures 1-3 which touch in a straight joint e . This joint lies parallel to the sides a , b . Both parts 6 and 7 are connected by a channel groove f and a corresponding projection g .

The characteristic feature of the trapezoidal tile which much be used in two positions reversed by 180° against each other causes in building curved or irregular streets the employment of special grooves or recesses and projections at the edges of each individual tile. Otherwise a great deal of types of plates must be on hand.

In the latter case two sets of plates can be constructed the one of which has on both inclined sides c and d only recesses the other only projections.

Better special plates are used as shown in Figures 1-3. On their wedge shaped sides c and d are arranged both a groove h and a projection i in such a manner that each half of the plate shows on the one side the groove on the other the projection. Two plates of this construction can be placed side by side putting the sides a , a and b , b of equal lengths in line or in reversed position, the sides a and b of different lengths. The projections i are shorter than the grooves h for the purpose that the plates can be shifted transversely.

Besides the recesses and projections or in the place of them the connections shown in Figures 1-3 near the corners and in Figures 11-14 in enlarged scale are suitable for locking trapezoidal tiles together.

These connections will not only serve for consolidating the surface of the pavement in first constructing the same but also facilitate afterwards the mending of displaced tiles.

The balls k represented in Figures 1, 2 and 11, 12 are inserted into a channel m formed in the front sides c , d of two adjacent tiles. The channel sides are preferably covered with metal layers n as shown.

The dimensions of the channels permit a movement to the ball k in the direction of the wedge edges c and d for the purpose of being shifted against each other. In longitudinal direction of the plates the ball is lying tight against metal layers n . The diameter of the ball therefore determines the narrowest seam or joint between two adjacent tiles.

Instead of a ball bearing a roller bearing may likewise be employed. The hollow bolts o shown in the Figures 1, 3 and 13, 14 are made of elastic material, preferably metal sheet, in the form of a cylinder and are provided for the same purpose as the ball, with the slight difference that the ball is rigid, whereas the bolt is yielding. In Figure 1 bolt joints are shown on the right hand side and they can be used together with the groove and projection connection. Also the bolts o are inserted into channels m .

The greater circumference of the bolt also makes it more fit in bearing which are not covered or coated on their inside with a metal layer.

The outer surface of the hollow bolt is either obliquely cut through and spirally wound, when the tiles are loaded as shown in Fig. 13, or cut transversely, so that the 5 cross-sections will stand in opposition to each other as shown in Fig. 14. The yielding action results in this latter case from the arrangement of extensions m' in the channel m into which the bolt enters, when 10 the bolts are inserted.

The outer diameter of the bolt may practically be chosen somewhat greater than the free-cross-section of the journal, and it therefore will fill out the bearing very snugly and 15 offer to the tiles a good yielding and resisting connection.

In case where the bolt is to be introduced into its journal from the outside the diameter of the bolt must be reduced in some degree, which may easily be done by means of 20 a tongue.

The proper weight of each tile effectively assists the mutual connection of the tiles in cases where the pavement is swelled or forms 25 an arch or vault which is directed downwardly, in this manner all joints of the pavement are equally closed. In the former practice where square tiles only were employed, its weight only closes the joints situated at 30 the longitudinal edges.

Figure 15 shows an embodiment of the present invention in which the shifting operation is facilitated. In this case iron fittings are used provided with a hole p and 35 connected with the tiles, the holes will coincide when the tiles are in the same mutual situation to each other. The holes or recesses p' are wide enough and arranged in such a manner that the edges of the tiles are 40 not altered, the bolt q may then easily be introduced into the recesses.

When the tiles are composed to build a pavement each tile is laid in such a manner that both the holes p will only permit 45 the introduction of the sharp point of the bolt q . By afterwards, driving in the bolt with power the tiles are rigidly connected together and the joint is rendered perfect.

By shaping the bolt 9 as a spring bolt 50 its yielding action tends to lock the joints automatically together in the event that ball bearings are provided. Percussions caused by the traffic will act in the same way, so that every enlargement of the joints is immediately at its generation automatically avoided.

Having now described the nature of my 55 said invention, I declare that what I claim is:

1. Paving plate comprising a body of trapezoidal shape, having grooves and projections at the inclined edges thereof arranged crosswise above and below the center line of the plate to engage correspond-

ing grooves and projections of an adjacent 65 plate either uniformly or displaced by an angle.

2. Paving plate, comprising a body of trapezoidal shape, having grooves at the inclined edges thereof and bodies arranged 70 movable in and displacable from said grooves and projecting from the edge of said plate to engage corresponding grooves so that the plates may be shifted transversely 75 to the track of the pavement.

3. Paving plate, comprising a body of trapezoidal shape, grooves as the inclined edges of the plate, projecting balls arranged in said grooves for the connection of adjacent plates in such a manner that they may 80 be shifted transversely to the track of the pavement.

4. Paving plate, comprising a body of trapezoidal shape, having grooves and projections at the inclined edges thereof arranged crosswise above and below the center line of the plate, and other grooves opening at the front edges of said body, bodies arranged displaceably in said other 85 grooves, and to project from the edges of 90 the plate and engage corresponding grooves of adjacent plates.

5. Paving plate comprising a body of trapezoidal shape, a groove along approximately one half of each of the inclined edges 95 of said body so as to extend somewhat beyond the center line of the plate, one of the two grooves being located above, the other below said center line, projections of smaller length than said grooves provided for at 100 the ungrooved parts of the converging edges and arranged in such a manner that adjacent plates may be displaced transversely to each other.

6. Cylindrically curved pavement for 105 streets, water courses, drains or the like, consisting of a plurality of curved plates of trapezoidal form arranged with their converging edges side by side, which plates have grooves and projections at their converging edges, the grooves and projections of adjacent plates engaging each other and permitting the single plates to be displaced transversely to the track of the pavement.

7. Cylindrically curved pavement for 115 streets, water courses, drains or the like, consisting of a plurality of curved plates of trapezoidal form arranged alternately in reverse relation so that the converging edges of each plate are adjacent the 120 reverse converging edges of adjacent plates, said edges of said plates having interengaging means connecting said plates together and permitting the single plates to be displaced transversely to the track of the 125 pavement.

8. Cylindrically curved pavement for 130 streets, water courses, drains or the like, con-

sisting of a plurality of curved plates of trapezoidal form arranged alternately in reverse relation so that the converging edges of each plate are contiguous to the reversely converging edges of the next adjacent plates, said plates having grooves and pro-

grooves and projections of adjacent plates engaging each other and permitting the single plates to be displaced transversely to the track of the pavement.

In testimony whereof I affix my signature.

PAUL NATTKÄMPER.
